BLAST FURNACE TUYÈRE

George E. Steudel, Chicago, Ill., assignor to Carnegie-Illinois Steel Corporation, a corporation of New Jersey

Application November 13, 1944, Serial No. 563,205

5 Claims. (Cl. 266—41)

This invention relates to tuyères and more particularly to water cooled tuyères for use in a blast furnace.

In the operation of blast furnaces, the bottom nose end of the tuyères are burned due to unfavorable conditions of the furnace burden which results in the formation of a dense area in line with the descent of the charge and substantially directionally below and in contact with the tuyère nose. This dense area aided by the chilling effect of the water cooled tuyère forms a pocket and prevents the descending globules of metal at the end of the tuyère from passing through to the hearth, thus forming a pool of metal, which, when it contacts the tuyère, burns the nose end and destroys its usefulness. This condition becomes increasingly serious as the linings of the furnace become worn. In order to increase the life of the tuyère, it has been suggested that an insert of a material having a high melting point be used in the bottom side of the nose end of the tuyère. While helpful, this suggestion does not eliminate or substantially reduce the dense area, but merely decreases its ill effects.

It is an object of this invention to reduce and move back the dense area by cutting back the bottom nose end of the tuyère.

This and other objects will be more apparent after referring to the following specification and attached drawing, in which:

Figure 1 is a longitudinal section of the tuyère as placed in the cooler of a blast furnace;

Figure 2 is a front view thereof; and

Figure 3 is a top view.

Referring more particularly to the drawing, the reference numeral 2 indicates the part of the furnace wall surrounding a cooler 4 which supports a tuyère 6 in the usual manner. As is customary, the tuyère consists of a substantially frusto-conical body 8 made of a copper alloy or other appropriate material and having the usual air passage 10 for the admission of a blast of air to the furnace, this passage being connected at its outer end with the source of air supply by means of a pipe 12. Surrounding the air passage 10 is a chamber 14 to which a cooling fluid is supplied by means of an inlet pipe 16. The fluid after passing through the chamber 14 is discharged from the top thereof through an outlet pipe 18. The body 8 has an outer nose portion 20 whose face inclines downwardly and inwardly at an angle of 20° from the uppermost and outermost portion of the air passage 10. The inclination of the nose face prevents the accumulation of the dense molten materials which usually collects around the underside of the nose of the tuyère, thus protecting the tuyère from burning. The angle of inclination 22 is prefer-

ably approximately 20°, but the benefits of the invention may be obtained by varying the angle between approximately 6° and 35°. Since the nose is cut back, the descending materials within the furnace have less tendency to pack at the bottom and foremost end of the tuyère, thereby increasing the porosity of the molten materials at this point with a resulting reduction of the dense area. The chilling effect of the tuyère is also farther back so that if a pocket should form at the bottom nose end, the globules of molten material, which drop past the upper front section of the tuyère, do not encounter the pocket and enlarge it, but continue to the hearth of the furnace.

15 While one embodiment of the invention has been shown and described, it will be apparent that other adaptations and modifications may be made without departing from the scope of the following claims.

20 I claim:

1. A tuyère comprising a body portion having an air passage therethrough, and an outer nose portion on said body having its face inclining downwardly and inwardly from the vicinity of 25 the uppermost and outermost portion of the air passage.

2. A tuyère comprising a body portion having an air passage therethrough, and an outer nose portion on said body having its face inclining 30 downwardly and inwardly at an angle of between approximately 6° and 35° from the vicinity of the uppermost and outermost portion of the air passage.

3. A tuyère comprising a body portion having an air passage therethrough, a cooling chamber in said body surrounding said air passage, and an outer nose portion on said body having its face inclining downwardly and inwardly at an angle of between approximately 6° and 35° from the 40 vicinity of the uppermost and outermost portion of the air passage.

4. A tuyère comprising a body portion having an air passage therethrough, a cooling chamber in said body surrounding said air passage, and an outer nose portion on said body having its face inclining downwardly and inwardly at an angle of approximately 20° from the vicinity of 45 the uppermost and outermost portion of the air passage.

5. A tuyère comprising a frusto-conical body having an air passage therethrough, a cooling chamber in said body surrounding said air passage, and an outer nose portion on said body having its face inclining downwardly and inwardly at an angle of approximately 20° from the uppermost and outermost portion of the air 50 passage.

GEORGE E. STEUDEL.
